(Cl. D44—22)

To all whom it may concern:

Be it known that we, Raymond J. Hansen and Oliver W. Hamilton, both citizens of the United States of America and both residing at Burbank, in the county of Los Angeles, State of California, have invented a new, original, and ornamental Design for Salt and Pepper Set, of which the following is a specification, reference being had to the accompanying drawing, forming part thereof, in which:

Fig. 1 is a front elevational view of a salt and pepper set, showing our new design;

Fig. 2 is a side elevational view, and

Figs. 3 and 4 are respectively top and bottom views thereof.

We claim:

The ornamental design for a salt and pepper set, substantially as shown.

RAYMOND J. HANSEN.
OLIVER W. HAMILTON.
